(57) **CLAIM**

I claim the ornamental design for a pocket key organizer, substantially as shown and described.

DESCRIPTION

FIG. 1 is a front perspective view of the pocket key organizer; FIG. 2 is a front view of the pocket key organizer; FIG. 3 is a rear view of the pocket key organizer; FIG. 4 is a left side view of the pocket key organizer; FIG. 5 is a right side view of the pocket key organizer; FIG. 6 is a top view of the pocket key organizer; FIG. 7 is a bottom view of the pocket key organizer; FIG. 8 is a left side view of the pocket key organizer; and, FIG. 9 is a left side view of the pocket key organizer. The features shown in broken lines in the various Figures are for illustrating the environmental structure and form no part of the claimed design.
